APPARATUS FOR RECORDING THE OPERATION OF CONTROL LEVERS OF ELECTRICALLY DRIVEN VEHICLES

Robert S. Clark, Albany, N. Y., assignor, by mesne assignments, to F. N. Bard, Chicago, Ill.

Application September 13, 1947, Serial No. 773,826

6 Claims. (Cl. 346—34)

1

This invention relates to means for recording the operation of the control levers of an electrically driven vehicle, as, for example, the throttle and reverse levers of a Diesel-electric locomotive. There are two control systems in common use on Diesel-electric locomotives: the two-lever system and the three-lever system. The former comprises a throttle lever and a reverse lever; the latter comprises, in addition, a selector lever which may also serve to operate a dynamic brake. This invention is concerned primarily with the two-lever system, although it could, of course, be used to record the operation of the throttle and reverse levers of a three-lever system.

The control stand of a two-lever system is equipped with a throttle lever and a reverse lever. When the locomotive is to proceed in a forward direction, the engineer swings the reverse lever from "neutral" to "forward" through an arc of some 30°, and then moves the throttle lever notch-by-notch through an arc, which at maximum speed amounts to some 90°, there being an automatic transition from one wiring arrangement to another, after a predetermined set of conditions have been established. The speed and power is determined by the position of the throttle lever. To reverse, the reverse lever is swung from "neutral" to "reverse" and the throttle lever manipulated as before.

It is an object of the present invention to provide means for recording the operation of the throttle and reverse levers on the speed tape of a recording speedometer by means of a single stylus or pencil, and a further object so to place the throttle lever record on the tape that the direction of movement of the locomotive, whether forward or reverse, shall be indicated. I attain these objects by the use of the following mechanism: The throttle lever is connected to a cam in a cam box by means of a flexible shaft or by direct linkage. As the throttle lever is swung, the cam in the cam box is rotated and a vertical cam follower, connected to the end of a fulcrumed rocker arm, is raised or lowered. The other end of the rocker arm is connected to a recording pencil in the speed-recording instrument. Thus movements of the throttle lever produce vertical lines on the speed tape, connected by horizontal lines indicating movement of the locomotive. As the throttle lever is manipulated precisely the same way, whether the locomotive is going forward or backward, it would be impossible to tell from the record, just described, in what direction the locomotive was moving when the record was made. In order to indicate the direction of locomotive movement, I have provided a second cam in the cam box, operated by the reverse lever, which raises the fulcrum of

2

the rocker arm when the locomotive is in reverse, and lowers it when the locomotive is going forward, or vice versa. As a result, operation of the throttle lever during forward movement is recorded on half the tape, whereas the same operation, when the locomotive is reversing, is indicated on the other half. It is, therefore, easy to tell from an inspection of the tape what direction the locomotive was moving at the time the record was made.

In the accompanying drawings I have illustrated a preferred embodiment of my invention. In these drawings,

Figure 1 is a schematic elevation of a control stand of a two-lever system equipped with the recording mechanism of my invention;

Figure 2 is a plan view of the stand shown in Figure 1, with the recorder eliminated;

Figure 3 is a front elevation of the cam box 15 with the covers removed showing the condition of the mechanism when the reverse lever is set at "forward" and the "throttle" lever at the "off" position;

Figure 4 is a horizontal section, on a somewhat larger scale, taken along line 4—4 of Figure 3;

Figure 5 is a front elevation similar to Figure 3, but showing the condition of the mechanism at full throttle forward;

Figure 6 is a rear elevation of the cam box 20 with the covers removed showing the condition of the mechanism when the reverse lever is set at "neutral" and the throttle lever at the "off" position;

Figure 7 is a detail showing how the flexible shaft, acting as a rack, meshes with one of the operating sheaves; and

Figure 8 is a section of a typical speedometer tape showing the record of the throttle lever operation made by the mechanism of this invention superimposed upon the speed record.

The control stand 10 comprises a main housing 11 on which is mounted a secondary housing 12. The throttle lever 13 is pivoted at 14 within the secondary housing 12 and projects outwardly through a horizontal slot 15. This lever is designed to be swung step-wise through an arc of 90° nine equi-spaced notches being provided to determine nine positions of the lever and eight relative speeds plus an "idle" and an "off" position. The reverse lever 16 is pivoted at 17 within the main housing 11, and projects outwardly through a slot 18 in its outer wall. This lever is designed to swing through an arc of some 64° and to occupy three positions: "Neutral," in the center of the arc; "reverse," at one end and "forward," at the other.

The inner end of the throttle lever 13 is fixed to a shaft 19 which carries a sheave 21 at its

lower end. A flexible, push-pull shaft 22, acting as a rack meshes with the sheave 21, in the manner shown in Figure 7, and passes through the usual guide tubing to the cam box 23. A similar horizontal sheave 24 is fixed to the lower end of a shaft 25 to which the inner end of the reverse lever 16 is fixed. This sheave 24 likewise meshes with a flexible shaft 26 which leads to the cam box 23. Thus, as the throttle and reverse levers are manipulated, the flexible shafts 22 and 26 move longitudinally toward and away from the cam box 23 and actuate the mechanism which I shall now describe.

The cam box 23 comprises a top 27, a bottom 28, sides 29, and a front and back, not shown. It is supported upon standards 31. Two horizontal bars 32 extend across the lower end of the box and serve to support the bearings for the cam shafts 33 and 34. Mounted near one end of shaft 33 is the throttle lift cam 35 and near the other end a sheave 36 which meshes with and is actuated by the flexible shaft 22, which in turn is actuated by the sheave 21, rotatable with the throttle lever. Mounted near one end of shaft 34 is the reverse lift cam 37 and near the other end a sheave 38 which meshes with and is actuated by the flexible shaft 26 which in turn is actuated by the sheave 24, rotatable with the reverse lever.

Three pairs of vertical rods 39 extend from the top 27 to the bottom 28 of the cam box and on these, three blocks 41, 42 and 43 are slidably mounted. A rocker arm 44 is fulcrumed at 45 on the middle block 42, one forked end of this arm embracing a pin 46 on block 43, the other forked end a pin 47 on block 41. A cam roller 48, mounted on block 43, engages the throttle lift cam 35, and so raises and lowers block 43 when the cam shaft 33 is rotated, thereby causing arm 44 to oscillate about its fulcrum 45 and raise and lower block 41 accordingly. A flexible shaft 49 is anchored to the top of block 41 and extends through the top 27 of the cam box to the recording instrument, indicated schematically at 51, where it actuates a pencil which makes a vertical mark on the horizontally moving speed tape by means well understood.

A cam roller 52, mounted on the middle block 42, engages reverse cam 37 and so raises and lowers block 42, when cam shaft 34 is rotated, thereby raising and lowering the fulcrum 45 of the rocker arm 44. The roller 52 is intended to engage the cam 37 in three positions: at 37a, at 37b, as shown in Figure 6, and at 37c, the second being slightly higher than the third. These three positions correspond with the "forward," "neutral" and "reverse" positions of the reverse lever, as will be explained presently.

The flexible shafts are wound with helical wire, as shown, which enables them to act as racks in engagement with the toothed sheaves 21, 23, 36 and 38. In order to hold the shaft in mesh with its sheave it is guided tangentially of the sheave and held thereby by means of its guide tube 53, cut away at 54 to permit entry of the sheave, as shown in Figure 7. The tube 53 extends beyond the point of tangency in a direction toward the end of the shaft, in order to accommodate the shaft in all positions of adjustment.

The apparatus, just described, operates as follows: When the engineer wants to start the locomotive moving in a forward direction, he swings the reverse lever from "neutral" position, as shown in Figure 6, to "forward" position. This rotates sheave 24, moves shaft 26 outward and downward into the cam box where it rotates

sheave 38 and cam shaft 34 and swings cam 37 counterclockwise (as shown in Figure 6), whereupon roller 52 moves down to the minimum lift position of cam 37. Then the engineer moves the throttle lever forward, notch-by-notch. As the throttle lever is moved, the sheave 21 is rotated and shaft 22 thrust downward in the cam box, rotating cam shaft 33 clockwise (as shown in Figure 3) and moving cam 35 into engagement with roller 48 on block 43. As cam 35 continues to rotate, block 43 is raised and with it pin 46, which causes the rocker arm 44 to swing about its fulcrum 45, lowering block 41, which pulls with it shaft 49 and the recording pencil in the instrument housing. As the records are made upside down, the result is a series of steps ascending upward from the median line of the tape to the top, as shown at the left-hand end of the tape of Figure 8. When the throttle lever is at rest the record will level off as a straight horizontal line. Meanwhile the speed will have increased as shown by the speed curve just under the throttle line.

In stopping or reducing speed, the operation of the throttle lever is reversed until the train comes to a halt, whereupon the engineer shifts his reverse lever to "neutral." This pulls the shaft 26 upward and, through the cam box mechanism previously described, swings cam 37 clockwise to the position shown in Figure 6, thus slightly raising block 42 and fulcrum 45, with the roller 52 riding upon the central position 37b of the cam. This moves the recording pencil to the middle of the tape in the instrument housing.

To reverse, the engineer swings the reverse lever back to "reverse." This completes the rotation of cam shaft 34 and moves the maximum lift 37a of the cam to a position directly under the roller 52, and as there is a pronounced rise from 37b to 37c, the block 42 and consequently fulcrum 45, block 43 and the recording pencil are moved a distance approximately half the width of the tape to their uppermost positions. Manipulation of the throttle lever now provides a step-like record as before, but starting from the bottom edge of the tape and ascending toward the median line. In short, the position on the tape of the throttle lever record tells at a glance whether the locomotive was going forward or reversing when the record was made.

In the light of the foregoing explanation we can now analyze the record shown on the tape of Figure 8, beginning at the left-hand end. As the throttle lever record is in the upper half of the tape, the locomotive was proceeding in the forward direction when the record was made. The engineer, starting from rest, and with his reverse lever at "neutral" and his throttle lever at "off," shifted the reverse lever to "forward" and notched his throttle lever ahead through eight speeds. An appreciable time interval intervened between successive shifts to enable the speed to accelerate, the horizontal lines indicating the length of the periods between shifts. Meanwhile, the speed curve shows the acceleration of the speed. When the throttle lever reached the last notch, the engineer left it there and the record leveled off, as shown. The speed also leveled off, as shown by the speed curve. We now note that the throttle lever curve starts to move down indicating that the engineer, although still moving forward, was swinging the lever back toward "off" and slowing down. After swinging back through two notches he permitted the locomotive to run at a reduced speed for an appreciable length of time, as indicated by the long horizon-

tal line. He then stepped down to "off" in six short steps, and when the locomotive came to rest, as indicated by the speed curve, swung the reverse lever through "neutral" to "reverse." This is indicated by the sharp vertical drop in the throttle lever curve. The engineer then started to manipulate his throttle lever again, but this time the record was on the lower half of the tape, which indicates that he was backing up. Having backed up for a short distance and coming to a stop, he then shifted his reverse lever to "forward," indicated by the sharp rise in the throttle lever curve, and notched forward one notch. Once more coming to rest, he shifted his reverse lever to "reverse" and backed a short distance. Then he swung his reverse lever to "forward" and proceeded to move ahead.

A record such as the one just described gives a complete and accurate picture of the engineer's manipulation of the throttle and reverse levers and the speeds at which they were manipulated. If he has failed to abide by the rules and regulations governing the operation of his locomotive, that fact will be plainly shown on the tape. All this is accomplished by the use of a single pencil in addition to the speed pencil.

It is, of course, possible to provide the speedometer dial with a second hand connected with the flexible shaft 49 so that a visual indication of the throttle lever operation can be had, the position of the reverse lever being indicated by the quadrant of the dial over which the hand is moving. This is less important than the making of a record, but would afford opportunity for an inspector in the cab to follow the engineer's operations without watching the control stand. However, present I. C. C. regulations do not permit two indications of the same operation to be visible to the operator or engineer, and as in most installations the control stand has numbered dials or some similar arrangement indicating the position of the control levers, it would be necessary to blank these off if the suggested indicating hand were provided.

I claim:

1. In apparatus for recording on a moving tape by means of a pencil the operation of an electrically driven vehicle controlled by a throttle and a reverse lever, the combination of a rocker arm pivoted between its ends, a connection between one end of the arm and the pencil to cause the pencil to move in unison with said end of the arm, means actuated by the reverse lever for shifting the pivot of the rocker arm in the plane of rocking movement of the arm, and a connection between the other end of the arm and the throttle to cause said end of the arm to move to different positions, as the throttle is moved to different settings.

2. In apparatus for recording on a moving tape by means of a pencil the operation of an electrically driven vehicle controlled by a throttle and a reverse lever, the combination of a rocker arm pivoted between its ends, a connection between one end of the arm and the pencil to cause the pencil to move in unison with said end of the arm, means actuated by the reverse lever for shifting the pivot of the rocker arm in the plane of rocking movement of the arm, a connection between the other end of the arm and the throttle to cause said end of the arm to move to different positions, as the throttle is moved to different settings, and guide means for guiding the ends of the arm and the pivot thereof along parallel paths.

3. In apparatus for recording on a moving tape by means of a pencil the operation of an electrically driven vehicle controlled by a throttle and a reverse lever, the combination of a block mounted for reciprocating movement, means connecting the block and reverse lever and causing the block to move in unison with the lever, a rocker arm pivoted between its ends on the block, means connecting one end of the arm and pencil and causing the pencil to move in unison with said end of the arm, and means connecting the other end of the arm and the throttle and causing rocking of the arm as the throttle is moved.

4. In apparatus for recording on a moving tape by means of a pencil the operation of an electrically driven vehicle controlled by a throttle and a reverse lever, the combination of a block mounted for reciprocating movement, a cam engaging the block and rotatable to move the block, means connecting the cam and reverse lever and causing rotation of the cam as the reverse lever is moved, a rocker arm pivoted between its ends on the block, means connecting one end of the arm and pencil and causing the pencil to move in unison with said end of the arm, and means including a cam for connecting the other end of the arm and the throttle and causing rocking of the arm as the throttle is moved.

5. In apparatus for recording on a moving tape by means of a pencil the operation of an electrically driven vehicle controlled by a throttle and a reverse lever, the combination of three blocks mounted for parallel reciprocating movement, a rocker arm pivoted between its ends on the middle block and having its ends connected to respective outer blocks, means connecting the middle block to the reverse lever and causing that block to move in unison with the lever, a connection between one outer block and the pencil and causing the block and pencil to move in unison, and means connecting the other outer block and the throttle and causing that block to move in unison with the throttle.

6. In apparatus for recording on a moving tape by means of a pencil the operation of an electrically driven vehicle controlled by a throttle and a reverse lever, the combination of three blocks mounted for parallel reciprocating movement, a rocker arm pivoted between its ends on the middle block and having its ends connected to respective outer blocks, a connection between one outer block and the pencil to cause the block and pencil to move in unison, cams engaging the middle block and the outer block, respectively, and rotatable to move said blocks, a connection between the reverse lever and the middle block cam to cause the lever to rotate said cam, as the lever is moved, and a connection between the throttle and the outer block cam to cause the throttle to rotate said cam, as the throttle is moved.
